INSULATOR SUPPORT

Rogers Case, Orange, N. J., assignor to Transandean Associates, Inc., Orange, N. J., a corporation of Delaware

Application August 4, 1948, Serial No. 42,530

2 Claims. (Cl. 248—220.5)

1

This invention relates to an insulator-supporting pin for attaching insulators of glass, porcelain, rubber or other suitable material on the cross arms of poles included in the lines of communication systems and like electrical wire lines.

In previous practice such insulator pins have been made of steel, iron or the like and particularly of steel which is galvanized to increase its resistance to corrosion. In practice and this is particularly necessary in the case of glass insulators, lead sleeves are interposed between the insulator engaging thread of the pin and the body of the insulator or a threaded wooden structure known as a cob is engaged with the head of the pin and in turn has threaded engagement with the body of the insulator. Such insulator pins of steel or iron are both unnecessarily heavy and relatively expensive to manufacture, inasmuch as they involve the initial forging of the pin structure and a subsequent threading operation performed at the head as well as at the shank of the pin.

I have discovered that insulator pins may be composed of bodies and heads made integral by casting a "light" metal selected from magnesium, aluminum and the magnesium and aluminum alloys, with increased ease of manufacture and with marked improvement in the utility of the pin in its function of mounting the insulator on the cross arm of the pole. It is an accepted fact that for most of their uses in the arts magnesium and aluminum seldom are used in their pure form but that the "light" metals called "magnesium" and "aluminum" as comprised in manufactured articles, usually include varying proportions of alloying metals. As is most convenient, the terms "magnesium" and "aluminum" as herein used are to be understood as defining primarily the useful alloys of magnesium and aluminum in which those metals preponderate. In casting the "light metal," the operation is performed by closed-mold casting, and as herein used the word "casting" is thus to be taken as qualified to a method of casting appropriate to the metal which is cast.

The threaded shank of the insulator pin by which it is attached to a cross arm or analogous structure being desirably of steel, iron or other metal having relatively great tensile strength to provide improved shear resistance in this portion of the complete pin, is integrated with the body of the insulator pin in suitable manner as by threading, welding or the like, and can be integrated in the pin structure by being cast into

2

the body of the insulator pin during the formation of the latter.

I have discovered that an insulator pin of this sort possesses adequate strength and possesses many advantageous features in use as well as in the simplicity of its manufacture. Since magnesium and aluminum are highly resistant to corrosion, no galvanizing is necessary to retard corrosion. The omission of galvanizing not only reduces the cost of manufacture but eliminates an undesirable feature of insulator pins as previously made. Galvanizing invariably causes roughness in the threading at the head of the insulator pin, which roughness scores the glass or other substance of insulator bodies mounted on the head of the pin, if the substance of the insulator at any point comes into direct contact with the head, or "thimble" of the pin.

Previously, the heads of galvanized steel and iron insulator pins have been spaced substantially from the glass of the insulators as by the use of wooden cobs or lead sleeves. Lead sleeves are separate elements added to the insulator pins when mounting the insulators thereon, and if omitted or if carelessly installed such sleeves have failed wholly to prevent scoring the bodies of the insulators by the rough galvanized threads on the heads of the insulator pins. Such lead sleeves tend to lose their effectiveness by deterioration in long continued use, and this is particularly the case when the insulator is mounted in locations in which it is subjected to continuous or frequently repeated vibration or shocks. Any slight scoring of the insulator bodies, and particularly if the insulators are composed of glass, makes them susceptible to breakage under abrupt changes in temperature and under slight blows which would not destroy an unscored insulator body or even under the effect of vibration. Wooden cobs are also separate elements which require an additional and careful operation in mounting them on the insulator pins. Even with care, there is great loss because of the splitting of wooden cobs as they are applied to the insulator pins.

Not only are the corrosion-resistant properties of magnesium and aluminum such that galvanizing with its introduced surface roughness is avoided, but it is also a fact that when formed in a die-casting operation the threads cast on the heads of the insulator pins have a particularly smooth surface which is incapable of scoring the contacted surface of a glass insulator body. Further assurance against scoring the metal of insulators mounted on the pins is pro-

vided by the fact that the designated "light" metals and a wide range of their alloys are much softer than iron, steel and the like heavy structural metals.

There is also the surprising fact that the magnesium and aluminum insulator pins are at least as resistant to deflection, or bending, as are steel insulator pins. Deflection tests under equal loads show that the resistance of the pins and the steel pins initially are almost equal. Because, however, the steel pins deteriorate by corrosion, over long periods of time and pins composed of the light metal promise greater serviceability in maintaining accurate alignment and spacing of the line wires.

For this reason I cast as integral structures the bodies and threaded heads, or at least the threaded heads, of insulator pins from a "light" metal as above defined. With the body of this structure the threaded shank of the insulator pin, which is of metal such as steel or iron possessing greater shear-resistance than that of the light metals, is integrated during the casting operation or in other suitable manner.

Generally stated, the object of my invention is to provide a metal insulator pin on which an insulator of glass or other suitable insulating material is mountable in direct contact with the metal head, or thimble, of the insulator pin; the thimble of the insulator pin being so composed and so formed that the metal of the thimble does not scratch or score the substance of the insulator at its bore, that the insulator is not broken by thermal expansion of the thimble and the engagement of the insulator and thimble is not loosened by thermal contraction of the thimble in variations of atmospheric temperature.

In the accompanying drawings:

Fig. I is an elevational view of my insulator pin.

Fig. II is a plan view of the insulator pin shown in Fig. I.

Fig. III is a view showing the head of the insulator pin as in Fig. I, in elevation on an enlarged scale and showing in section of a spool-form insulator of conventional form thereon.

Fig. IV is a vertical sectional view through the terminal shank region of the insulator pin showing a bolt, or threaded stem, secured thereto.

Referring to Fig. I of the drawings, the insulator pin therein shown comprises an integrally cast body having a body, or shank, region 1 which is circular in cross section, a squared region 2 adjacent the base of the pin structure and a circular flange, or base, 3. Extended inwardly from the outer surface of base 3 axially of the shank there is a threaded socket 4 for the reception of a threaded attaching stem. Head 5 of the insulator pin is tapered upwardly and the thread 6 cast on the head is shown, as is most desirable as a square face, or approximately square face, thread giving what is in effect an integrally cast cob to which the insulator A shown in Fig. III of the drawings is applied. It will be noted that the insulator A is in direct contact with the head of the insulator pin. The insulator may be composed of glass, hard rubber, porcelain or other suitable vitreous or non-vitreous material which is electrically non-conductive. Because the head or thimble, of the insulator pin is composed of the relatively soft "light" metal and is ungalvanized, it does not tend to score the opposed surface of the non-metallic insulator in contact of the threaded head 5 of the insulator pin with the cooperatively threaded bore a of the insulator. The avoidance

of this scoring which would occur if the head of the insulator pin were of relatively hard ferrous metal and particularly if the insulator pin had been galvanized to present a roughened surface, is important with respect to insulators composed of any suitable insulating material. It is of particular importance if the insulator be composed of glass the tendency of which to fracture under wide temperature swings is greatly intensified by even slight surface scoring.

For attachment of the insulator pin to a cross arm an attachment pin is connected to the lower region of the insulator pin proper. Such attachment pin may be of any length appropriate to the mounting of the pin on a wooden or metal cross arm, may be secured in the shank of the insulator pin proper in any suitable manner as noted above and may carry any suitable means for securing the assembly to the cross arm. As shown, such attachment pin is in the form of a threaded stud or shank 7 engaged in threaded socket 4 of the insulator pin and is provided with a nut 8 for engaging the remote surface of the cross arm.

The general suitability of a light metal of the designated sort to use in direct contact with an insulator, even if such insulator be composed of glass, has been explained above. Even if composed of such metal, however, there remains the problem of thermal expansion and contraction of the insulator pin under wide temperature swings. I have compensated for such problem in satisfactory manner by longitudinally slotting the thimble 5 of the insulator pin throughout its diameter and throughout a large proportion of its longitudinal extent. As shown, this slot 9 is of substantial width to provide an effective bodily resilience to the thimble of the pin and adequately to compensate for thermal expansion and contraction at both high and low atmospheric temperatures.

In diametrically adjusting the thimble of the insulator pin and the bore of the insulator, the relationship is made such that at normal or room temperature the thimble of the insulator pin fits tightly in the bore of the insulator with slight bodily compression in such fit. If then the assembly be subjected to substantial rise in temperature the tendency of the insulator pin thimble by its thermal expansion to crack the insulator is neutralized to an adequate extent by movement of the segmental sections of the thimble 5 toward each other. That is, the reaction to the pressure of the thimble against the bore of the insulator is to decrease the width of slot 9 so that the insulator body is not subjected to the full force of the expansion. Similarly the thimble being slightly compressed in the bore as initially introduced thereinto, the shrinkage of the diametrical dimension of the thimble likewise is compensated. That is, the spring action provided by slot 9 and the initial compression of the thimble causes the thimble to remain in close engagement with the bore of the insulator in spite of the thermal contraction of the thimble. It is to be understood that compensation to thermal expansion and contraction of the insulator pin thimble under swings of atmospheric temperature can be compensated by slotting the thimble of the insulator pin otherwise than as shown and described. I have found that the single longitudinally extended slot as shown provides in simple manner compensation adequate to prevent breakage of the insulator or loosening of the insulator on the insulator pin caused by expansion or contraction of the thim-

ble. Also, though less desirably, the thimble and shank of the insulator pin may be made of different metals, as for example by elongating and thickening the attaching bolt or stud of ferrous metal or the like, and engaging it with a longitudinally extended skirt or base of the thimble. In any event, however, the thimble is cast of one of the designated light metals and is slotted in compensation for its thermal expansion and contraction.

The insulator pin of my invention thus presents great advantage in avoiding the loss through breakage and deterioration of wooden cobs and the breakage of sleeves composed of lead and the like. It avoids the destructive effects of bringing a metal thimble of an insulator pin as previously composed into direct contact with the insulator by the nature of the metal of which the insulator pin is composed and by the compensation to atmospheric temperature changes provided by the slotted thimble. As noted, the slotted thimble maintains a tight engagement of the insulator with the insulator pin at low atmospheric temperatures and conversely avoids breakage of the insulator by thermal expansion at high atmospheric temperatures.

I claim as my invention:

1. An insulator pin arranged for engagement with cross arms and the like comprising a shank, and a threaded insulator-carrying thimble cast

20

of one of the "light" metals or their alloys comprising magnesium and aluminum, said thimble being divided longitudinally therethrough by a diametric approximately parallel-side slot, the slotting of the said thimble compensating for thermal expansion and contraction of the thimble with respect to an insulator supportingly engaged thereby.

5 2. An insulator pin arranged for engagement with cross arms and the like comprising a shank and a threaded insulator-carrying thimble integrally cast of one of the "light" metals or their alloys comprising magnesium and aluminum, said thimble being divided longitudinally therethrough by a diametric approximately parallel-side slot, the slotting of the said thimble compensating for thermal expansion and contraction of the thimble with respect to an insulator supportingly engaged thereby.
